A. PAPINI.

ELECTRIC HEATER FOR WATER AND OTHER LIQUIDS,
APPLICATION FILED AUG. 28, 1919.

1,335,020.

Patented Mar. 30, 1920.

Antonio Papini, ^{INVENTOR}
BY *Dederlein & Fairbanks*
ATTORNEYS.

UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

ELECTRIC HEATER FOR WATER AND OTHER LIQUIDS.

1,335,020.

Specification of Letters Patent. Patented Mar. 30, 1920.

Application filed August 28, 1919. Serial No. 320,444.

To all whom it may concern:

Be it known that I, ANTONIO PAPINI, a subject of the King of Italy, having resided in the United States one year last past and having declared my intention of becoming a citizen thereof, residing in the city and county of Philadelphia, State of Pennsylvania, have invented a new and useful Electric Heater for Water and other Liquids, 10 of which the following is a specification.

My invention consists of a novel construction of an electric heater for water or other liquids wherein I employ an outer casing provided with an inner lining of porcelain 15 or the like within which is supported a body having a resistance wound thereupon whereby the water or other liquid is heated, a novel construction of carbon comb electrodes being employed, which are disposed in series 20 with the heating element or resistance coil, whereby the presence and the absence of the water to be heated closes and opens respectively the electric circuit whereby the device is automatic in its operation and only 25 operative when it contains a certain amount of the liquid to be heated, or when the water level has reached a certain point, so that there is no waste of electricity, and the device is automatic, economical and reliable in 30 its operation at all times. It further consists of a novel construction and manner of assembling the carbon comb electrodes, whereby the device is rendered automatic in its operation, the circuit being open and closed 35 according to variations in the water level.

It further consists of a novel manner of mounting and supporting said carbon comb electrodes with respect to the body or muffle supporting the resistance or heating element, so that all the parts are readily accessible for the purposes of replacement, inspection or repairs. Attention is directed to 40 my co-pending application for carbon comb electrode, Serial No. 320,445.

For the purpose of illustrating my invention, I have shown in the accompanying drawings forms thereof which are at present preferred by me, since they will give in practice satisfactory and reliable results, but 45 it is to be understood that the several instrumentalities of which my invention consists can be variously arranged and organized and that my invention is not limited to the precise arrangement and organization of

these instrumentalities as herein shown and 55 described.

Figure 1 represents a vertical, sectional view of an electric water heater embodying my invention.

Fig. 2 represents a section on line 2—2 60 Fig. 1.

Fig. 3 represents a diagrammatic view of the carbon comb electrodes, the resistance and their adjuncts.

Similar numerals of reference indicate 65 corresponding parts in the figures.

Referring to the drawings,

1 designates my novel construction of electric heater for water and other liquids, the same comprising the outer casing 2, 70 which is preferably widened at its upper portion and provided with the internal porcelain lining or bushing 3, within which is contained the porcelain resistance supporting body 4, which is supported within the 75 casing in any suitable manner, said body having the lower flange 5 which is provided with the vertical slots 6 for permitting the circulation or upward flow of water which enters the casing 1 through the inlet 7, the 80 water after being heated flowing from said casing through the port 8 in the upper portion of the lining 3, and the outlet 9.

10 designates ports in the upper portion of the body 4, above the top of which are 85 located the carbon comb electrodes 11 and 12, the same being supported in any suitable manner and preferably respectively formed of a vertical wall 13, having the laterally extending or projecting members 90 14, and the vertical wall 15 having the projecting or lateral members 16, said members 14 and 16 being arranged in staggered or alternating order, as will be understood from Figs. 1 and 3. The resistance wire 17 95 is wound around the body 4, and it will be understood that since said resistance is in series with the battery of carbon comb electrodes 11 and 12, that the current entering by the conductors 18 and 19 flows to the 100 upper member 16 of the electrode 12, through the loop 21, back to the conductor 22 which passes through the insulating sleeve 23, said conductor leading to the conductor 24, and said sleeve 23 passing through ports or open- 105 ings 35 in the elements 14 and 16.

25 and 26 designate insulating devices or bushings and nuts for the conductors 18

and 24 which are carried by the cover 27, which incloses the top of the device, said cover being held in position by the ring 28 or any other suitable fastening device. The 5 top of the porcelain lining 3 may be conveniently held in position by the flange 29, which may rest on the upper edge 30 of the casing 2.

31 designates a filtering screen for the inlet pipe 7, and 32 designates a settling 10 chamber or impurity collecting chamber, provided with the outlet 33 and blow-off cock 34.

The operation is as follows:—

15 The various parts having been assembled and correlated as seen in Fig. 1, it will be apparent that the battery of carbon comb electrodes 11 and 12 is in series with the heating element or resistance 17, and the 20 water or other liquid to be heated having been admitted at 7 fills all the available space, thereby establishing electric communication or contact between the carbon comb electrodes 11 and 12.

25 As the flow of water is controlled or shut-off at the inlet 7 by any suitable means, when the water rises to a predetermined height with respect to said electrodes, the 30 circuit will be closed thereby, and the heated water between the electrode elements 14 and 16 will partly flow out at the outlet 9 and partly vaporize, so that when the water level has fallen a certain predetermined amount, the circuit automatically 35 opens and there is no waste of electricity. The current flows from the conductors 18 and 19 to the upper element 16 of the comb electrode 12, through the water or other liquid to be heated to the elements 40 14 of the electrode 11 to the resistance 17, the loop 21 to the conductor 22, and conductor 24.

In case it is desired to obtain access to the interior it is only necessary to remove 45 the top or cover 27, whereupon all the parts are readily accessible for the purposes of inspection, replacement or repair. The screen or strainer 31 will arrest all ordinary impurities and any further impurities 50 collected in the sediment chamber 32 can be blown off upon opening the cock 34.

By the provision of the ports 5 and 10 in the body 4 and the ports 35, an effective circulation is provided for the liquid to be 55 heated and while I have described my invention as particularly applicable to heating water, it will be understood that any other liquid or fluid desired can be heated therein.

60 It will be understood that wherever desired, any necessary insulation for the various elements may be provided in addition to that specified herein, as will be apparent to those skilled in the art.

65 It will be apparent that my novel device

has no movable parts and is designed to close and open the circuit automatically when water is admitted and shut off respectively. It will be found to be efficient with either hard or soft water, and the battery 70 of carbon comb electrodes is preferably of relatively low ohmic resistance when in water, said battery being connected in series with the heating element of due resistance.

75 It will now be apparent that I have devised a novel and useful construction of an electric heater for water and other liquids which embodies the features of advantage enumerated as desirable in the 80 statement of the invention and the above description, and while I have, in the present instance, shown and described a preferred embodiment thereof which will be found in practice to give satisfactory and 85 reliable results, it is to be understood that the same is susceptible of modification in various particulars without departing from the spirit or scope of the invention or sacrificing any of its advantages.

90 Having thus described my invention what I claim as new and desire to secure by Letters Patent, is:—

1. In an electric water heater, a casing, an inlet and outlet therefor, a porcelain lining 95 thereof, a resistance supported in the lower portion thereof, and carbon comb electrodes supported in the upper portion of said casing and adapted to be wholly or partly submerged by the liquid to be heated, whereby 100 upon variations in the level of said liquid corresponding variations of resistance in said carbon comb electrodes will be obtained.

2. In an electric water heater, a casing, a resistance supported in the lower portion 105 thereof, and carbon comb electrodes supported in the upper portion of said casing, one terminal of said resistance being connected to one of said electrodes, and the other terminal thereof to a conductor, said 110 carbon comb electrodes being adapted to be wholly or partly submerged by the liquid to be heated, whereby upon variations in the level of said liquid corresponding variations of resistance in said carbon comb electrodes 115 will be obtained.

3. In an electric heater for water or other conducting liquids, an outer casing, an inner lining therefor, a resistance supporting body contained within said lining, a battery of 120 carbon comb electrodes supported above said body, a cover for said casing, conductors supported in said cover, one terminal of said resistance being connected to one of said electrodes, and the other terminal thereof 125 leading to one of said conductors.

4. In an electric heater for water or other liquids, an outer casing, an inner lining therefor, a resistance supporting body contained within said lining and having ports 130

- at its top and bottom, a resistance supported on said body, a carbon comb electrode having projecting elements supported above the top of said body and connected to one terminal of said resistance, a second carbon comb electrode having also projecting elements arranged in staggered order with reference to said first mentioned elements, said electrodes being located in the upper portion of said casing, conductors leading exteriorly from said casing, and an electrical connection from said resistance to one of said conductors.
5. In an electric heater for water or other liquids, an outer casing, an inner lining therefor, a resistance supporting body contained within said lining and having ports at its top and bottom, a resistance supported on said body, a carbon comb electrode having projecting elements supported above the top of said body and connected to one terminal of said resistance, a second carbon comb electrode having also projecting elements arranged in staggered order with reference to said first mentioned elements, said electrodes being located in the upper portion of said casing, conductors leading exteriorly from said casing, and an electrical connection from said resistance to one of said conductors.
10. In an electric heater for water or other liquids, an outer casing, an inner lining therefor, a resistance supporting body contained within said lining and having ports at its top and bottom, a resistance supported on said body, a carbon comb electrode having projecting elements supported above the top of said body and connected to one terminal of said resistance, a second carbon comb electrode having also projecting elements arranged in staggered order with reference to said first mentioned elements, said electrodes being located in the upper portion of said casing, conductors leading exteriorly from said casing, and an electrical connection from said resistance to one of said conductors.
15. In an electric heater for water or other liquids, an outer casing, an inner lining therefor, a resistance supporting body contained within said lining and having ports at its top and bottom, a resistance supported on said body, a carbon comb electrode having projecting elements supported above the top of said body and connected to one terminal of said resistance, a second carbon comb electrode having also projecting elements arranged in staggered order with reference to said first mentioned elements, said electrodes being located in the upper portion of said casing, conductors leading exteriorly from said casing, and an electrical connection from said resistance to one of said conductors.
20. In an electric heater for water or other liquids, an outer casing, an inner lining therefor, a resistance supporting body contained within said lining and having ports at its top and bottom, a resistance supported on said body, a carbon comb electrode having projecting elements supported above the top of said body and connected to one terminal of said resistance, a second carbon comb electrode having also projecting elements arranged in staggered order with reference to said first mentioned elements, said electrodes being located in the upper portion of said casing, conductors leading exteriorly from said casing, and an electrical connection from said resistance to one of said conductors.
25. In an electric heater for water or other liquids, an outer casing, an inner lining therefor, a resistance supporting body contained within said lining and having ports at its top and bottom, a resistance supported on said body, a carbon comb electrode having projecting elements supported above the top of said body and connected to one terminal of said resistance, a second carbon comb electrode having also projecting elements arranged in staggered order with reference to said first mentioned elements, said electrodes being located in the upper portion of said casing, conductors leading exteriorly from said casing, and an electrical connection from said resistance to one of said conductors.

tion of said casing, conductors leading exteriorly from said casing, and an electrical connection from said resistance to one of said conductors, in combination with an insulating sleeve passing through ports in the projecting elements of said electrodes, said last mentioned connection passing through said sleeve.

6. In an electric heater for water or other 35 conducting liquids, an outer casing, an inner lining therefor provided with an upper flange supported on the top of said casing, a cover detachably secured to said casing, an inlet and an outlet for said casing, said lining having a port communicating with said outlet, a resistance supporting body contained in said casing and having upper and lower ports therein, a resistance carried by said body, conductors supported in said 40 cover, and carbon comb electrodes in the upper portion of said body and in series with said resistance.

ANTONIO PAPINI.
